Oscar T. Gandy his Atty.

UNITED STATES PATENT OFFICE.

ANDREW H. TEEPLE, OF RUTHERFORD, NEW JERSEY, ASSIGNOR TO HEADLEY AND FARMER COMPANY, OF HARRISON, NEW JERSEY, A CORPORATION OF NEW JERSEY.

SAMPLE-TRUNK.

No. 920,217.

Specification of Letters Patent.

Patented May 4, 1909.

Application filed January 2, 1909. Serial No. 470,373.

To all whom it may concern:

Be it known that I, ANDREW H. TEEPLE, a citizen of the United States, and resident of Rutherford, in the county of Bergen and State of New Jersey, have invented certain new and useful Improvements in Sample-Trunks, of which the following is a specification.

This invention relates to improvements in sample trunks, and particularly to that class of sample trunks which are used for containing and displaying garments.

The object of my invention is to provide a new and improved trunk of this kind which is simple in construction, composed of few parts, is strong and durable, not apt to get out of order, and in which the garment can be quickly packed conveniently on hangers and when desired can be displayed to great advantage.

In the accompanying drawings in which like characters of reference indicate like parts in all the figures: Figure 1 is a perspective view of my improved sample trunk, opened up for display purposes. Fig. 2 is a perspective view of the same, the parts being folded. Fig. 3 is a vertical sectional view of one end part of the trunk, showing details.

The trunk proper is constructed with a body 1, and lid 2 of any style, shape or material in the conventional manner. A screw socket or floor plate 3 is secured to the upper surface of the floor 4 of the trunk body 1, at one end thereof and into this socket a tube 5 is screwed which extends to the top edge of the trunk body and terminates in eye 6 to which an eye 7 is pivoted by a bolt 8, said latter eye being secured on one end of a rod 9. A yoke 10 is secured on the inner surface of one end wall 11 of the trunk near the top edge of the body and embraces the tube 5 loosely so that said rod has slight play toward and from the inner surface of said end wall 11. The rod 9 terminates at its free end in a head 12 provided with a cross pin 13. On the inner surface of the opposite end wall 14 and at the upper edge thereof a socket 15 is secured, adapted to receive the head 12 and its cross pin 13. A follower 16 of conventional construction fits within the trunk body, but is made shorter than the trunk body so as to allow for an open space for the collar and shoulder parts of garments, which cannot be compressed or packed as closely as the body portions of the garments. A longi-

tudinally sliding bar 17 is mounted and guided on the follower 16 and is provided with a longitudinal slot 18 through which a binding screw 19 passes, and serves for locking the sliding bar in place on the follower, at any adjustment required on the sliding bar. A set of notched jaws 20 are secured on the free end of the sliding bar 17 and are adapted to receive between them the head 12 and to engage the cross pin 13. 60 65

The garments are hung on coat hangers of conventional shape, as for example shown at 21, and provided with hooks 22. The garments are hung in conventional manner, on the hangers 21 and placed in the trunk, the hooks 22 engaging the bar 5 and the follower 16 is placed upon the uppermost garments, the trunk being on end. The rod or bar 9 is swung into position so that its head 12 and cross pin 13 rest in the socket 15 as shown in Fig. 2. The rod or tube 9 is made of such length that when its head 12 is forced into the socket 15 the upper end of the tube 5 is moved slightly toward the inner surface of the end wall 11 so as to bind the hooks 22 between said tube 5 and the inner surface of the end wall 11. After closing the lid or cover the trunk is now ready for shipment. 70 75 80

When the garments are to be displayed, the trunk is placed on end, as shown in Fig. 2, and the follower is removed, the sliding bar 17 is moved upward as far as necessary and then locked in place by means of the binding screw 19. The rod or tube 9 is then swung into horizontal position and the cross pin 13 is engaged with the notches in the jaws 20, the follower 16 having been placed into vertical position the requisite distance from the opened trunk. The hooks 22 of the hangers 21 supporting the garments are unhooked from the tube 5 and hooked upon the horizontal rod or tube 9 and can be properly spaced for display purposes. The tube or rod 9 is supported at one end by the vertically standing follower 18 and its extension 90 95 100 bar 17 and at its opposite end by the hasp or yoke 10 secured to the inner surface of the end wall 11 and embracing the tube 3.

Having described my invention what I claim as new and desire to secure by Letters Patent is:

1. In a sample trunk, the combination with a trunk body, of a tube secured therein to the floor and extending along one wall to the upper edge of the trunk body, a yoke 111

loosely surrounding the upper edge of said tube and secured to the trunk body, a rod pivoted to the outerend of said tube, a socket on that wall of the trunk opposite the one at 5 which the said rod is hinged and adapted to receive the free end of said rod, a follower and means on the same for engaging the free end of said rod, substantially as set forth.

2. In a sample trunk, the combination 10 with a trunk body, of a tube secured therein to the floor and extending along one wall to the upper edge of the trunk body, a yoke loosely surrounding the upper end of said

tube and secured to the trunk body, a rod pivoted to the outer end of said tube, a socket 15 on that wall of the trunk opposite the one at which the said rod is hinged and adapted to receive the free end of said rod, a follower, an adjustable bar on said follower, means for locking said bar in place and means on said 20 bar for engaging the free end of said rod, substantially as set forth.

ANDREW H. TEEPLE.
